UNITED STATES PATENT OFFICE.

WILL E. KELLER, OF LOS ANGELES, CALIFORNIA.

CONCRETE WALL CONSTRUCTION.

Application filed August 7, 1926. Serial No. 127,739.

My invention has relation more specifically to a wall mold construction of the "slip form" type for forming hollow concrete walls and simultaneously forming a plurality of concrete bonds between the wall members to tie the same together.

In U. S. Patent No. 1,566,135 entitled Wall bonding device issued December 15, 1925 to Clara Y. Waugh as administratrix 10 of the estate of James H. Waugh, deceased, and assigned in full to me, a bonding construction was illustrated and described in which the wall members were held in bonded relation to each other by metal rods having hooked ends. In order to provide for the proper placement of the metal bonds during the wall pouring operation, relatively long "ladders" carrying metal bonding rods were required to be set in position prior to 20 the operation of pouring the wall members, this procedure not only entailing considerable trouble but increasing the cost of erection.

In the present invention such "ladders" 25 or supports for metal bonding rods are dispensed with, the concrete bonds which serve to tie wall members together being formed during the concrete pouring operations without the use of special devices other than 30 the usual "slip form" molds that are required in the erection of the wall.

It is therefore a general object of the invention to avoid a waste of time in forming the wall member bonds, to reduce the expense of erection, and to enable the formation bonds simultaneously during the pouring of the wall members.

Other objects and advantages will be apparent from the following specification, references being had to the accompanying drawings forming a part thereof, in which:

Fig. 1 is a transverse vertical section of the "slip form" mold in connection with a hollow concrete wall construction.

Fig. 2 is a detail perspective view of the lower portion of the mold form, illustrating the means employed in forming the concrete wall bonding members.

Fig. 3 is a perspective view of a portion 50 of a finished hollow wall, showing the concrete bonds connecting the wall members.

Fig. 4 is a partial plan view of a hollow concrete wall partly in section together with 55 the mold forms.

Fig. 5 is a partial transverse vertical sec-

tion through the hollow wall showing the method of inserting metal reinforcing rods in the concrete bonds.

Fig. 6 is a detail sectional side elevation of 60 a pair of adjacent core boxes showing the first step in forming a concrete bond.

Fig. 7 is a view similar to the above showing the second step with the reinforcing rods in position in the partially formed 65 bond.

Fig. 8 is a similar view showing a completed bond.

Fig. 9 is a view similar to the above showing the mold form moved upwardly in position to form another bond. 70

Fig. 10 is a perspective view of one of the mold form core boxes.

This invention is designed to be employed in connection with concrete slip 75 forms of the type illustrated in the Waugh patent above referred to, the construction, arrangement, and means for continuously raising the form during the formation of the wall being exactly similar, with the exception of the arrangement of the core forms between the wall members. These core 80 members being altered in order that the concrete bonds may be intermittently formed during the wall pouring operations. 85

Mold walls of wood planking for forming the hollow wall are arranged in pairs 10, 11, and 12, 13, each pair being spaced apart between which the concrete is poured to form the wall members 14, 15. The outer 90 faces of walls 10, 13, are rigidly connected together by means of longitudinally extending beams 16, 17, 18, spaced apart, while walls 11, 12, constitute the side walls of a plurality of core boxes 19, closed at their 95 upper and lower ends by end boards 20, 21. These core boxes are of the same height as the outer faces of mold walls 10, 13, and are spaced apart longitudinally the approximate width of the concrete bonds adapted to be 100 formed during the erection of the wall members as will be more fully described hereinafter.

Bolted or otherwise secured to the outer faces of beams 16, 17, 18, are a plurality of 105 vertically extending beams 22, 23, spaced apart a suitable distance, their upper ends extending above the upper edge of the side mold walls 10, 13, and each oppositely disposed pair are tied together with transversely disposed timbers 24, 25, spaced apart. Disposed transversely upon the upper edges 110

of the mold wall 10, 13, and the upper face of a longitudinally extending beam 26, bolted to the upper end plates 20, of the core boxes 19, are beams 27, spaced apart, their ends extending beyond the outer faces of the vertically extending beams 22, 23 to form a support for a platform 28 for the workmen. Inclined braces 29 are provided to tie the beams 27 to the lower ends of beams 22, 23.

Mounted in the foundation 30 of the hollow wall are a plurality of vertically disposed reinforcing rods 31, the rods extending upwardly through each wall member 14, 15, slightly greater than the entire height of the finished wall. These reinforcing rods are connected to a form elevating mechanism, and as such mechanism is exactly the same as described in the Waugh patent, no further description of the same is thought to be necessary, especially as such mechanism forms no part of this invention.

The bonding members 40 in this case which serve to tie the two wall members together are formed wholly of concrete, although metal reinforcing rods may be introduced therein if thought desirable, and are preferably formed in spaced vertical rows and a distance apart equal to the length of the core boxes 19, as clearly shown in Fig. 3.

Each of the four vertical edges 41 of the core boxes are grooved for the reception of wood slide plates 42, and it is thought the method of forming the bonds may be more readily understood by a description in connection with Figs. 6 to 9 inclusive of the drawings. In Fig. 6, the movable slip form is illustrated in position at the foundation 30 of the wall members, in this position slip boards 42 are first placed in the corner grooves of the oppositely disposed ends of two adjacent core boxes 19, the height of these boards are approximately one half of the height of the boxes. Cross boards 43, are then laid across the upper ends of boards 42, their ends projecting slightly beyond the side faces of the core boxes, see Fig. 2. Concrete is then poured between the mold forms to a height just above the boards 43, (see Fig. 7) and metal reinforcing rods 44 may be then introduced if desired. After the same have been placed in position other slip boards 45 exactly similar to boards 42 are inserted in the corner grooves of the core boxes, their lower ends being disposed above the cross boards 43 a distance equal to the desired thickness of the bond. The pouring of concrete in the molds is again resumed as shown in Fig. 8, the wet concrete pouring through the openings formed by the cross boards 43 and the lower ends of the slide boards 45 and forming a complete concrete bond between the wall members.

After the above described operations are completed the slip forms are moved up-

wardly to the position shown in Fig. 9, when other cross boards 43 are again laid across the upper ends of the lower slide boards 42, as described and shown in Fig. 6. The above operations are continued until the entire wall members have been poured, the concrete bonds 40 being formed at regular intervals as shown in Fig. 3.

It will be understood that when the forms are moved upwardly in order to add to the height of the wall members, the slip boards 42 will be held against movement by their adhesion to the inner faces of the formed wall members, but if found desirable they may be knocked out of place after the walls have been formed.

It will be readily apparent from the above description that by the employment of core boxes in a slip form construction and spacing the abutting ends in spaced relation, in combination with side slip boards and cross boards that concrete bonds may be formed at regular intervals between the two wall members as the concrete is poured, the bonds as effectively tying the walls members together as the metal bonds on the rods in the patented structure hereinbefore referred to.

What I claim is:

1. A concrete mold form comprising a movable mold form consisting of a plurality of walls spaced apart to form mold cavities adapted to be utilized in the formation of a pair of hollow wall members, and means connected to some of said mold form walls and removable therewith for forming a plurality of concrete bonding members adapted to connect or tie the wall members together as the same are poured.

2. A concrete mold form of the "slip form" type comprising a movable mold form consisting of a pair of outer mold walls spaced apart, a mold wall member interposed in the space between the mold walls and movably connected to said mold form, and means connected to the mold wall member for forming concrete bonds between the wall members as the same are poured.

3. In a concrete mold form of the "slip form" type, comprising a movable mold form consisting of a pair of vertically disposed mold walls spaced apart, a plurality of core boxes disposed between the said mold walls to form mold cavities between the mold walls and the side faces of the core boxes, the ends of said core boxes being also spaced apart, said core boxes movably connected to said mold form and adjustable members mounted between the adjacent ends of the core boxes, whereby the concrete may run from one mold cavity to the other during the wall pouring operation to form concrete bonds between the wall members.

4. A concrete mold form construction of the "slip form" type comprising a movable mold form consisting of a pair of vertically

disposed mold walls and means for moving the same as the concrete is poured, a plurality of core boxes mounted between the mold walls and movable therewith to form mold cavities between the outer faces of the core boxes and the vertical mold walls, the end walls of said core boxes being spaced apart, and means mounted between the ends of the core boxes for forming concrete bonds between the mold cavities when concrete is introduced therein.

5. A concrete mold form of the "slip form" type including vertically disposed mold walls, a plurality of core boxes mounted between said walls and movable therewith adapted to form wall mold cavities on

either side of the core boxes, the end walls of the core boxes being spaced apart, a pair of slide plates mounted in the spaces between the side walls of adjacent core boxes, each pair being in vertical alinement, the upper being vertically movable to form an opening between the oppositely disposed ends of each pair of slide plates, and a cross plate adapted for placement across the upper ends of the lower oppositely disposed slide plates adapted to form a support for the concrete bond as the walls members are poured.

In witness that I claim the foregoing I have hereunto subscribed my name this 15th day of July, 1926.

WILL E. KELLER.
